UNITED STATES PATENT OFFICE

CHARLES F. RICHARDS, OF WHITE HAVEN, PENNSYLVANIA

HYDRAULIC COAL AND ORE WASHING AND SEPARATING MACHINE

Application filed October 29, 1927. Serial No. 229,533.

This invention relates to a flotation process, or an ascending current of water through the material to be separated, as a means for separating the lighter particles from the heavier.

5 The invention contemplates a traveling screen as means for supporting the material during the separating process, and in the preferred structure the screen consists of a drum arranged to receive the material upon its top portion, water being supplied to the interior of the drum and passing upwardly through the openings thereof and through the material thereon and separating the lighter from the heavier particles.

10 15 The invention includes means for retarding the movement of the material, changing the speed of the traveling screen and varying the pressure of the water, all as will appear more fully hereinafter.

20 25 While the drawing illustrates a preferred embodiment of the invention, it is to be understood that in adapting the means to meet specific needs and requirements the design may be varied and such other changes in the minor details of construction may be resorted to within the scope of the invention as claimed, without departing from the spirit thereof.

30 For a full understanding of the invention and the merits thereof, reference is to be had to the following description and the drawing hereto attached, in which,

35 Figure 1 is a vertical, central, longitudinal, sectional view of an embodiment of the invention.

Figure 2 is a top plan view thereof.

Figure 3 is a vertical transverse sectional view on the line 3—3 of Figure 1, looking in the direction of the arrows.

Figure 4 is a detail sectional view on the line 4—4 of Figure 1, looking to the left as designated by the arrows.

Corresponding and like parts are referred to in the following description and designated in the several views of the drawing by like reference characters.

The numeral 1 designates generally a substantial framework for receiving and supporting the operating parts. The numeral 2 designates a tank which is adapted to contain a quantity of water for washing the coal, ore

or other commodity to be separated. An outlet 3 is formed in the bottom of the tank for the discharge of slush and this opening is controlled by means of a gate 4 which is operable by means of a lever 5 conveniently positioned. 55 A portion of the tank 2 is upwardly and rearwardly inclined from the slush outlet 3, as indicated most clearly at 6 in Figure 1. This inclined portion 6 is constricted as indicated most clearly in Figure 3 to provide a trough in which operates the lower run of an endless conveyor 7. Spur wheels 8 and 9 support the endless conveyor 7. The upper spur wheel 9 is fast to a shaft 10 which is connected by means of a drive belt 11 to a drive shaft 12 of a 60 variable speed gearing. A chute 13 is provided at the receiving end of the tank 2 for directing the material into the separator. An angular lip 14 is pivotally connected to the lower or discharge end of the chute 13 and is 65 adjustable vertically at its lower or discharge end. Vertically disposed rods 15 are connected at their lower ends to the lower delivery portion of the lip 14 and their upper ends are threaded and receive hand wheels 16 which engage brackets 17 through which the upper threaded ends of the rods 15 loosely pass.

70 A gate 18 is pendant from a transverse shaft 19 mounted in brackets 20 applied to the upper portion of the frame work 1. The gate 18 controls the speed of the material over the chute 13. A bell crank 21 is mounted upon a standard 22 projected upwardly from the framework 1 and its vertical arm is connected by means of a rod 23 with an arm pendant from the shaft 19. The horizontal arm of the bell crank 21 is provided with a weight 24 which is adjustable thereon, and is connected by means of a rod 25 with an arm 26 projecting rearwardly from a pivotally mounted gate 27 which controls the outlet for the slate. When the feed controlling gate 18 swings rearwardly it also effects a corresponding movement of the gate 27 through the instrumentality of the connecting means. 85 Adjustment of the weight 24 on the horizontal arm of the bell crank 21 controls the resistance offered by the gate 18 to the feed of the material. An upright plate 28 is disposed rearwardly of the feed chute 13 and 90 95 100

its bottom edge is about in the plane of the delivery portion of the angled lip 14. The outlet closed by the gate 27 is located below the plate 28. A plate 29 extends rearwardly and downwardly from the top edge of the plate 28 and the coal or other separated commodity passes thereover. The plates 28 and 29 extend transversely between the sides of the tank 2. The upright plate 28 inclines forwardly from its bottom edge. A gate 30 is placed against the forward side of the plate 28 and is adjustable vertically in suitable guides 31 applied to opposite sides of the tank. A rod 32 projects upwardly from the gate 30 and its upper end is reduced and threaded and receives a hand wheel 33 which engages and rests upon a bracket 34 mounted upon a cross piece of the framework. Manipulation of the hand wheel 33 effects vertical adjustment of the gate 30 to regulate the overflow of the coal or other commodity to be separated and discharged over the plate 29. A deflector 35 is placed upon the plate 29 and is disposed midway between the sides of the tank 2 and its side portions are reversely inclined, as indicated most clearly in Figures 3 and 4 to deflect the coal or other commodity towards the side of the tank. A wall 36 closes the sides of the coal receiving compartment opposite that closed by the plate 28 and openings are formed therein for the discharge of the coal. Gates 37 close the said discharge openings and each is adjustable by means of a rod 38, the upper end of which is threaded to receive a hand wheel 39. A chute 40 leads rearwardly and downwardly from each of the discharge openings to deliver the coal or other commodity at the predetermined point. The chutes 40 are located upon opposite sides of the trough 6 through which the heavier articles are discharged by means of the conveyor 7.

A traveling screen 41 closes the space formed between the angle lip 14 and the plate 28 and preferably consists of a perforated drum mounted upon a shaft 42 which is mounted in suitable bearings provided at opposite sides of the tank 2. The shaft 42 is connected with the changeable speed gearing operated by shaft 12 which may be of any construction and which is connected to the shaft 10 by means of the drive belt 11. A drive pulley 43 fast to the shaft 10 is adapted to receive power from a suitable source not shown, said power being transmitted to the changeable speed gearing 12 which admits of the rotary screen 41 being driven at different speeds. A shield 44 fits snugly against the bottom and opposite sides of the rotary drum 41 and is circularly adjustable to vary the position of its extremities with reference to the lip 14 and plate 28. The shield 44 is of circular outline and is flanged at opposite ends to receive bolts 45 which secure the shield 44 to the sides of the tank in the required ad-

justed position. Slots 46 are formed in the flanges at the ends of the shield to receive the fastenings 45 and thereby admit of circumferential adjustment of the shield. The openings formed in the sides of the drum 41 are arranged in parallel rows and in consequence water forced upwardly through the openings escapes in jets in a radial direction. Hence, adjustment of the shield controls the jets adjacent the delivery end of the lip 14. Water from a suitable source is supplied to an end of the drum 41 by means of a pipe 47 in which is located a valve 48 which admits of controlling the flow so that the force of the jets escaping through the openings of the drum 41 may be regulated.

In the operation of the separator the coal is supplied thereto in any manner and is received upon the chute 13, over which it gravitates, the gate 18 opening to regulate the feed. The gate 27 opens simultaneously with the gate 18, the weight 24 being adjusted to regulate the feed as required. It is assumed that the screen 41 is rotated at the required speed and that the water is supplied to the screen at the required pressure. The lip 14 is adjusted to retard the discharge of the material from chute. The shield 44 is adjusted to regulate the jets escaping through the openings of the drum 41 adjacent the lip 14. As the material finally discharges over the lip 14 the heaviest particles will drop and fall into the boot or lowest portion of the tank and be discharged through the trough 6 by means of the conveyor 7. The material falling upon the drum is subjected to the upwardly ascending current of water which carries the lighter particles upwardly, the heavier particles remaining at the lowest level. The slate and rock pass through the openings controlled by the gate 27 and drop into the lower portion of the tank and are carried off by the conveyor 7. The lighter particles, such as coal, are carried upwardly and pass over the plate 28 onto the plate 29 and are directed laterally by means of the deflector 35 and pass through the discharge openings controlled by means of the gate 37 and pass off by way of the chutes 40. The gate 30 may be adjusted vertically to regulate the overflow of the discharge of the lighter particles.

Having thus described the invention, I claim:

1. An ore and coal separator comprising a tank, a feed chute provided with an adjustable angle lip, a gate suspended above the feed chute, a gate for controlling the discharge of the heavier particles separated from the material, connecting means between the two gates to cause them to move in unison, means for varying the resistance to the opening of the gate, a screen adapted to receive the material to be separated, an overflow for the lighter particles separated from the mate- 130

rial, an adjustable gate for varying the over-flow, and a plate for receiving the overflow.

2. In an ore and coal separator, the combination of a rotary separating screen, a feeder for supplying the material to the upper portion of the screen to one side of a vertical plane passing through the axis of the screen, means within the screen for projecting jets upwardly therethrough and through the material passing thereover, and a shield snugly fitting against the bottom and opposite sides of the screen and circumferentially adjustable to regulate the effectiveness of the jets on the material passing over the screen.

15 In testimony whereof I affix my signature.
CHARLES F. RICHARDS. [L. S.]
